UNITED STATES PATENT OFFICE.

THOMAS S. GILL, OF DADE CITY, FLORIDA, ASSIGNOR OF ONE-HALF TO JEFFERSON D. SUMNER, OF DADE CITY, FLORIDA.

CHURN-DASHER.

No. 895,399.

Specification of Letters Patent

Patented Aug. 4, 1908.

Application filed November 13, 1907. Serial No. 402,039.

To all whom it may concern:

Be it known that I, THOMAS S. GILL, a citizen of the United States, residing at Dade City, in the county of Pasco and State of Florida, have invented a new and useful Churn-Dasher, of which the following is a specification.

This invention relates to a churn dasher of that type which is adapted to reciprocate vertically in the cream containing barrel or tub which it more or less closely fits as a plunger or piston.

The invention has for one of its objects to provide a piston form of dasher, provided with a plurality of passages, which divides the cream up into separate streams as the cream passes from one side of the dasher to the other by the up and down movement of the latter.

A further object of the invention is to arrange the passages in such a way that there is a confluence of the streams passing through each pair of adjacent passages, as the dasher moves in one direction, and a divergence of the streams as the dasher moves in the opposite direction, so that the cream will be thoroughly agitated and quickly changed into butter.

With these objects in view, and others, as will appear as the nature of the invention is better understood, the invention comprises the various novel features of construction and arrangement of parts, which will be more fully described hereinafter and set forth with particularity in the claims appended hereto.

In the accompanying drawing, which illustrates one of the embodiments of the invention, Figure 1 is a plan view of the dasher showing a portion broken away at one pair of the passages. Fig. 2 is a bottom plan view. Fig. 3 is a side view of the dasher partly broken away at one pair of the passages to illustrate their shape and arrangement.

Corresponding parts in the several figures are indicated throughout by similar characters of reference.

Referring to the drawing, 1 designates the body of the dasher which is preferably, though not necessarily, made of wood in the form of a disk. At the center of the body is provided an opening 2 for receiving the dasher rod, which may be of ordinary form. The diameter of the disk-shaped body 1 is

taining barrel or tub with which it is to be used.

Suitably displaced around the body, at points slightly inward from the periphery thereof, are pairs of passages 3; in the present instance these pairs of passages are displaced ninety degrees from each other, such an arrangement being preferable for small sized dashers. In larger sizes, the adjacent pairs of passages may, with advantage, be arranged at a smaller angle apart. The passages of each pair are arranged with their axes inclined toward each other in an upward direction, and the passages are arranged in such proximity that they intersect at their upper ends so as to have a common upper opening 4, the lower openings 5 being distinct and independent. By this arrangement, a wedge-shaped partition 6, as shown in Fig. 3, is formed between each pair of passages. In transverse section, that is to say, in a plane transverse to the axis of each passage, the latter is circular, hence the openings 4 where the passages intersect at the top surface of the body 1 are slightly elliptical, as shown in Fig. 1. The edges of the bottom openings 5 are rounded at 7, so that each passage slightly contracts in an upward direction, as best shown in Fig. 3.

With a dasher of this construction, the downward movement of the dasher causes the passages 3 to divide the cream up into streams as the latter passes to the upper side, and the streams of each pair of passages meet as they pass out of the openings 4. On the up-stroke, the cream enters the opening 4 and the wedge-shaped portions 6, Fig. 3, act as splitters and divide the cream so as to pass out through the openings 5. In this manner, the streams come together on one stroke, and divide and separate on the other stroke, as the cream passes from one side of the dasher to the other. By the meeting of the passages of each pair, there is a tendency of the cream becoming compressed as it passes upwardly through the passages on the downward stroke, while on the upward stroke, this tendency does not exist. The action on the cream thus produced by the arrangement and shape of the passages causes a thorough agitation of the cream, so that the butter is quickly and readily formed.

I have described the principle of operation of the invention, together with the device which I now consider to be the best embodiment.

ment thereof, but I desire to have it understood that the device shown is merely illustrative, and that various changes may be made, when desired, as are within the scope of the invention.

What is claimed is:—

1. A churn dasher having a plurality of pairs of passages having independent openings at one end and a common opening at the opposite end.

2. A churn dasher having a plurality of pairs of passages, each pair of passages being arranged with their axes symmetrically in-

clined and having their corresponding ends meeting in a single opening.

3. A churn dasher having a pair of symmetrically inclined passages having separate openings on one side of the dasher and a common opening on the opposite side.

In testimony that I claim the foregoing as my own, I have hereto affixed my signature in the presence of two witnesses.

THOS. S. GILL.
